UNITED STATES PATENT OFFICE.

GEORGE ALBERT LYON, OF PHILADELPHIA, PENNSYLVANIA.

VEHICLE BUFFER DEVICE.

Original application filed October 5, 1921, Serial No. 505,468. Divided and this application filed June 8, 1923. Serial No. 643,661.

To all whom it may concern:

Be it known that I, GEORGE ALBERT LYON, a citizen of the United States, and resident of Philadelphia, county of Philadelphia, State of Pennsylvania, have made a certain new and useful Invention Relating to Vehicle Buffer Devices, of which the following is a specification taken in connection with the accompanying drawings.

10 This application is a division of my application Serial No. 505,468, filed October 5, 1921.

This invention relates to buffer or bumper devices for automobiles or other vehicles in which plates of spring steel or other suitable metal are slit or cut so as to form a series of vertically separated strips or members, some of which may be used as the buffer front strips or members, and adjustably or otherwise connected together, if desired, so as to form a double strength reenforced buffer front throughout the central part of the buffer between the automobile frame members. Some of these integrally connected strips stamped or cut from such plates may be bent inward and rearward to form attaching strips or members and may be given any suitable shape and construction so as to most conveniently and effectively 30 secure them to the automobile frame. In some cases the attaching strips may be forced or spread apart edgewise from the connected buffer front strips; so that, if desired, several inches of clearance can be secured in this manner, and it is usually desirable to have the buffer end somewhat reduced in width or rounded to decrease the weight and also to give increased resilience and a more pleasing appearance to this part

40 of the buffer. In some cases also several vertically separated front strips may be cut or stamped out of a single plate of such spring steel material and preferably connected to an intermediate rearwardly bent 45 attaching member or strip which may be indirectly or directly connected to the vehicle frame.

In the accompanying drawings showing in a somewhat diagrammatic way various 50 illustrative embodiments of the invention—

Fig. 1 is a perspective view of one form of buffer.

Fig. 2 is a plan view of the corresponding 55 spring steel blank showing the way in which the parts may be formed or cut out.

Fig. 3 is a similar view showing another form of blank.

Fig. 4 is a perspective view of the corresponding buffer which may be made therefrom, and

Fig. 5 is a detail view showing a modified construction.

In the form of buffer shown in Fig. 1 the front strips or impact receiving members, 1, 2, may be substantially horizontal or level, if desired, and are preferably substantially straight throughout their overlapping portions between the strip ends 7, 8; these overlapping portions being adjustably or otherwise connected as by the clips 14. These front strips may be bent backward somewhat outside of these overlapping portions, and for example, the strip 1 may have its outer portion 3 bent or curved back so as to merge into the reduced or tapered buffer end 4 which may be rounded on its tip as indicated. The buffer end is preferably integral with the vertically separated attaching strip or member 13 which may be bent backward from about the point or line of separation 15 so as to give a resilient support to the reenforced front strips, and also preferably to hold them in somewhat elevated position as is desirable in many cases. The corresponding front strip 2 may have a similarly rearwardly curved or bent outer portion 3, communicating with the reduced rounded end 12 and with the integral lower or vertically separated attaching member 13.

This desirable form of resilient buffer may be conveniently and cheaply made from sheet metal blanks, such as shown in Fig. 2; and these blanks may be preliminarily cut out in a suitable press or otherwise from the desired spring steel stock about a quarter to three-eighths of an inch thick more or less, and four to seven inches wide or so at the widest part. The blank where the greatest economy of stock is desired may be punched or otherwise severed along the longitudinal cut or lines of severance 5—10 and simultaneously or otherwise cut transversely as at the longitudinally separated points 6—9. The blank is thus severed into two parts, each of which has one long strip or member 1, 2 and a vertically separated shorter strip or member 11, 13; the length of these different parts being, of course, so chosen as to give the desired lengths in the attaching strips and

front strips of the buffer. Then the separated and slit blank sections may be bent, hardened and tempered and finished in any suitable way as by grinding processes before the final nickel-plating, enamel or other surface finish is given thereto. Of course, the main cutting, bending and shaping operations are more effectively done when the metal is hot and in some cases more or less of these shaping processes may be performed at the same heat at which the blank sections are finally hardened for tempering.

Fig. 3 shows another illustrative style or type of blank which may have reduced or 15 rounded ends 16, 17 and be correspondingly wider where three or more vertically separated buffer sections are formed from the same strip of material. Where three strip sections are formed, the blank may be six 20 or nine inches wide, a suitable width spring steel rolled stock which preferably has rounded edges being advisable for this purpose. Several longitudinal cuts or lines of severance 18-20 and 19-21 may be formed 25 in the blank and a series of transverse cuts or lines of severance 26-27 and 30-31 may be made by any suitable stamping or cutting device. In this case the blank is considerably longer than the complete buffer 30 front since after bending back the intermediate attaching strips or tongues 22-23 for instance and curving more or less the adjacent portions of the other vertically separated strips, they are arranged in overlapping 35 position as indicated in Fig. 4, the upper front strips 24-28 overlapping throughout a considerable distance if desired and being adjustably or otherwise held by any suitable clamping or connecting devices such as the Lyon type enclosing clips 40 32. The lower front strips or contact members 25-29 may similarly overlap if desired and may be adjustably or otherwise connected by the clips 33 so that a double height 45 contact face is provided on the buffer which has a desirable appearance and may be quickly and readily manufactured with very small percentage of waste stock. The buffer units may in this case be similarly hardened, tempered, polished and finished; and 50 they may be shipped in assembled condition or preferably in more or less nested closely packed condition where one set of front strips may closely overlap the other to form 55 a relatively small package. As shown in Fig. 5, the attaching and other front strips may be forced or spread apart edgewise so that, if desired, as much as several inches of 60 vertical clearance can be secured in this way between the outer edges of the attaching strip 22 and the buffer front strips such as 15.

This invention has been described in connection with a number of embodiments, 65 forms, proportions, parts, arrangements,

materials, methods of manufacture, connection and use, to the details of which disclosure the invention is not of course to be limited, since what is claimed as new and what is desired to be secured by Letters Patent is set forth in the appended claims:

1. The automobile buffer comprising two similar integral units of spring steel plate, each of said units comprising a rounded rearwardly bent buffer end and a connected 75 inwardly and rearwardly bent attaching strip and two connected relatively long vertically separated buffer front strips vertically separated from said attaching strips, said front strips being detachably connected 80 in laterally adjusted overlapping position to form double thickness reinforced contact portions adjacent the center of the buffer front.

2. The automobile buffer comprising two 85 integral units of steel plate, each of said units comprising a rounded rearwardly bent buffer end and a connected inwardly and rearwardly bent attaching strip and two connected 90 relatively long vertically separated buffer front strips, said front strips being connected in overlapping position to form double thickness reinforced contact portions adjacent the center of the buffer front.

3. The automobile buffer comprising two similar integral units of tempered spring steel plate, each of said units comprising a rounded buffer end and a connected inwardly and rearwardly bent attaching strip 100 and two connected relatively long vertically separated vertically aligned buffer front strips, said front strips being adjustably arranged in overlapping position and detachably connected.

4. The automobile buffer comprising two similar integral units of steel plate, each of said units comprising a rounded buffer end and a connected inwardly and rearwardly bent attaching strip and two connected 110 relatively long vertically separated buffer front strips, said front strips being adjustably connected in overlapping position.

5. The automobile buffer comprising two integral units of spring steel plate, each of said units comprising a reduced buffer end and a connected inwardly and rearwardly bent attaching strip and two connected relatively long vertically separated vertically aligned buffer front strips, said front strips 115 being detachably connected in overlapping position so as to be laterally adjustable.

6. The automobile buffer comprising two integral units of spring steel plate, each of said units comprising a reduced buffer end 125 and a connected inwardly and rearwardly bent attaching strip and two connected relatively long vertically separated buffer front strips, said front strips being connected in overlapping position.

7. The automobile buffer formed of steel plate, and comprising rearwardly and inwardly bent attaching strip portions and connected buffer end portions having a plurality of integrally connected inwardly extending vertically separated front strips forming vertically separated front contact portions and connecting devices to clamp together overlapping portions of the corresponding front strips.
8. The automobile buffer formed of tempered spring steel plate and having rounded buffer ends integrally connecting two vertically separated vertically aligned buffer front strips, and attaching strips bent inward and rearward from said buffer ends and adapted to be attached to the vehicle to support the buffer front strips therefrom, said buffer front strips extending inward from the buffer ends and being clamped in laterally adjusted position to form overlapping vertically separated front strips throughout the central part of the buffer front.
9. The automobile buffer formed of steel plate and having rounded buffer ends integrally connecting two vertically separated buffer front strips and attaching strips bent inward and rearward from said buffer ends and adapted to be attached to the vehicle to support the buffer front strips therefrom, said buffer front strips extending inward from the buffer ends and being clamped to form overlapping vertically separated front strips throughout the central part of the buffer front.
10. The automobile buffer formed of tempered spring steel plate and having reduced width buffer ends and two integrally connected vertically separated vertically aligned buffer front strips rearwardly bent adjacent said ends, and integrally connected attaching strips bent inward and rearward from said buffer ends and adapted to be attached to the vehicle to support the buffer front strips therefrom, said buffer front strips extending inward from the buffer ends and being connected to form overlapping vertically separated front strips throughout the central part of the buffer front.
11. The automobile buffer formed of spring steel plate and having reduced width buffer ends and two integrally connected vertically separated vertically aligned buffer
- front strips rearwardly bent adjacent said ends, and integrally connected attaching strips bent inward and rearward from said buffer ends and adapted to be attached to the vehicle to support the buffer front strips therefrom, said buffer front strips extending inward from the buffer ends to form vertically separated front strips.
12. The automobile buffer formed of tempered spring steel plate and having rounded buffer ends and a plurality of integrally connected vertically separated vertically aligned buffer front strips rearwardly bent adjacent said ends, and integrally connected attaching strips bent inward and rearward from said buffer ends and adapted to be attached to the automobile frame members to support the buffer front strips therefrom.
13. The automobile buffer formed of steel plate and having reduced width buffer ends and a plurality of integrally connected vertically separated vertically aligned buffer front strips rearwardly bent adjacent said ends, and integrally connected attaching strips bent rearward from said buffer ends and adapted to be attached to the automobile frame members to support the buffer front strips therefrom.
14. The automobile buffer formed of spring steel plate and having reduced width buffer ends and two integrally connected vertically separated vertically aligned buffer front strips rearwardly bent adjacent said ends, and integrally connected attaching strips extending inward and rearward from said buffer ends and adapted to be attached to the automobile.
15. The automobile buffer formed of steel plate and having reduced width buffer ends and two integrally connected vertically separated buffer front strips and integrally connected attaching strips extending rearward from said buffer ends and adapted to be attached to the automobile.
16. The automobile buffer formed of steel plate, and comprising rearwardly and inwardly bent attaching strip portions and connected buffer end portions having a plurality of integrally connected inwardly extending vertically separated front strips forming vertically aligned contact portions of the buffer front.

GEORGE ALBERT LYON.
